UNITED STATES PATENT OFFICE

98,433

DESIGN FOR A TEXTILE FABRIC

William R. Haywood, White Plains, N. Y.

Application December 23, 1935, Serial No. 60,229

Term of patent 3½ years

To whom it may concern:

Be it known that I, William R. Haywood, a citizen of the United States of America, residing in the city of White Plains, Westchester County, State of New York, have invented a new, original, and ornamental Design for a Textile Fabric, of which the following is a specification, reference being had to the accompanying drawing, forming part thereof,

The figure is a plan view of a textile fabric, showing my new design.

I claim:

The ornamental design for a textile fabric substantially as shown.

WILLIAM R. HAYWOOD.
